UNITED STATES PATENT OFFICE

ARTHUR E. DAVENPORT, OF MAYWOOD, ILLINOIS

OIL-DISPLAY PUMP

Application filed September 20, 1928. Serial No. 307,318.

The invention relates to oil measuring and dispensing apparatus of the type which includes a sight tube or chamber for indicating flow and for displaying the quality or character of the oil.

While the display provisions heretofore provided are more or less ingenious, they are objectionable for a number of reasons. These may be summarized as inaccessibility 10 or difficult accessibility due to faulty location so that in case of breakage the pump is idle for a considerable time and replacements are more or less expensive; failure to accomplish the ultimate object, that is to say to attract 15 and hold the attention of the customer; and the necessity of employing special relief devices to prevent the accumulation of air in the sight chamber.

My invention has for its general objects to 20 overcome the disadvantages of the old practice; to provide a simple and inexpensive sight chamber attachment which readily may be applied or removed and which conveniently substitutes for the usual elbow joint 25 that connects the upstanding delivery arm of the pump with the gooseneck or nozzle carrying extension thereof; to provide a sight chamber containing buoyant or mobile objects normally at rest in the bottom of the 30 chamber and which under flow of oil rise to the top of the chamber and when the flow ceases descend to their normal position; and to provide a sight chamber attachment which requires no pet cocks or other manually operated air relief devices, any air present 35 in the sight chamber or in the oil being automatically discharged through the delivery arm under pump impulse.

The invention is illustrated in the accompanying drawings wherein—

Figure 1 is a sectional elevational view of the improved attachment applied to the conventional delivery arm of a pump.

Fig. 2 is a top view of the combination bottom head and L unit.

Referring to the drawings, 5 represents the upstanding delivery arm of the conventional measuring and dispensing pump 6, and 7 represents its nozzle carrying horizontal extension. Elements 5 and 7 usually are joined

by an L. According to my invention I replace the latter with a device for diverting flow through a sight chamber so that the customer can be reasonably assured of quantity and quality of oil, it being a fact that 55 pumps have sometimes failed to deliver oil notwithstanding evidence of the meter to the contrary.

The replacement is a casting 8 having fluid ways 9 and 10 which, respectively, accommodate the arms or pipes 5 and 7. The disc shape top of the casting has a marginal rim or flange 11, and an axial fluidway 12. The annular pocket or well formed by the rim 11 and the neck 13 of fluidway 12 has one or 65 more ports 14 to pass oil delivered to the casting by the pump.

The top of the casting forms the basal support and lower head of an oil display chamber consisting of a glass cylinder 15 70 whose bottom edge is centered and protected by the marginal rim 11, and is secured against leakage by appropriate packing 16. A pipe 17, detachably mounted in the neck 13 of the axial fluidway 12, forms in conjunction with an upper head a tie for the cylinder. The upper head or dome 18 is equipped with packing and with a marginal rim or skirt 19 to protect the top edge of the cylinder. Upper head 18 has an axial 75 opening 20 whereby it is slidable on the central tubular support 17 in order properly to engage the upper rim of the cylinder 15. The protruding end of pipe 17 is threaded for the reception of an acorn or blind nut 21, 80 a lead or other gasket 22 being interposed between the nut and the top of the dome to insure rigid and proper sealing relation of the parts.

Pipe 17 is screwed into the neck 13 of the 85 axial fluidway 12 leading to the delivery arm and is equipped adjacent the dome of the cylinder with one or more lateral openings 23. The merit and advantage of this construction and arrangement is that as the oil rises in the cylinder it forces the air through the openings 23 and into the regular discharge channel. The openings 23, being at the extreme top of the cylinder, any air bubbles which may manifest themselves must neces- 95 100

sarily be carried away before the oil can enter the central delivery tube 17. There is always more or less air present in any oil and visible delivery devices have heretofore been equipped with pet cocks or other manually operated devices to get rid of the air in order to prevent compression on the pump stroke and expansion on the delivery. Failure to open the pet cock at regular periods to relieve the trapped air accounts in the main for the non-success of the visible device.

We come now to that part of the invention which provides for positive indication of flow and for attracting and holding the attention of the customer. As remarked at the outset, this is accomplished by locating within the chamber objects or devices, which are calculated by shape or color and position to arouse attention. Probably the simplest expedient of this nature is element 24. Elements 24 are hollow ball shape objects constructed of very thin celluloid, the walls being approximately .006 of an inch in thickness. They are formed or provided with small holes 25 for the passage of oil. Normally they are at rest in the bottom of the cylinder but when oil is flowing they rise continuously with the oil until the end of the delivery at which time they practically are at the top of the glass. They then descend slowly to normal position.

Having described my invention, I claim:
The combination with the delivery end of
35 oil dispensing apparatus, of a sight chamber
included therein, and free objects of greater
specific gravity than the oil and normally
at rest in the bottom of the chamber in the
absence of flow and which in response to
40 flow are mobile in the visible oil to attract
and hold attention thereto.

In testimony whereof I affix my signature.
ARTHUR E. DAVENPORT.
